ATTORNEY

UNITED STATES PATENT OFFICE

WILLIAM O. MCINTYRE, OF CHARLOTTE, NORTH CAROLINA

SAFETY CATCH

Application filed August 2, 1929. Serial No. 382,967.

My invention relates to safety catches for pins, and consists in the constructions, arrangements and combinations herein described and claimed.

- 5 It is an object of my invention to provide a pin-keeper embodying a swingable hook member frictionally retained in locked position, thus preventing accidental disengagement of the pin from the keeper.
- 10 A further object of my invention is to provide a simplified construction of pin-keeper in which the pivot for the swinging hook member is positioned a substantial distance from the base of the keeper, thus obviating damage of the pivot during mounting of the keeper upon an article of jewelry.

A still further object of the invention is the provision of a safety catch wherein outward swinging movement of the pin will tend to more effectively lock the pin within the keeper.

Additional objects, advantages and features of invention will be apparent from the following description, considered in conjunction with the accompanying drawings, wherein:

Figure 1 is a side elevation of an article of jewelry embodying my safety catch;

Figure 2 is an enlarged cross sectional view, on the line 2—2 of Figure 1;

Figure 3 is a cross section on the line 3—3 of Figure 2;

Figure 4 is a detail perspective view of the keeper member with the hook member detached.

In carrying out my invention I provide an article of jewelry, generally indicated by the reference character 1, upon one end of which there is swingably mounted a pin 2 having a piercing point 3 confined within a keeper 4.

The keeper 4 in the present instance is formed from a single piece of material having a base portion 5 adapted to be soldered or otherwise secured to the bar 1. The keeper 4 is bifurcated longitudinally of its length to provide a slot 6 for reception of the pin 2, the bifurcations extending from the outermost part of the keeper 4 and stopping short of the base 5, as clearly shown in Figures

2 and 4. A slot 7 is also formed in the material 5 and extends at right angles to the slot 6 and is of a width to accommodate a keeper-hook.

The keeper being thus formed, studs 8 and 9 are provided, extending at right angles to the base. The studs 8 are apertured adjacent their outer ends, adapted to receive a pintle 10 upon which there is swingably mounted a keeper-hook 11.

The hook 11 has a bill portion 12 adapted to lie within the boundaries of the stud 9 when in closed position, and one side of the bill is recessed, as at 13, adapted to register with a protuberance 14 of the stud 9. By this construction it will be seen that the keeper-hook 11 will be frictionally held against accidental movement.

Opposite the bill 12, the hook has a shank 15 of a length to extend closely adjacent the base 5, and has an offset portion 16 defining a gripping means 17 for swinging the hook 11. If desired a kerf 18 may be formed in the offset portion to accommodate a finger nail of the user, for manipulating the hook.

As shown in Figure 2, the offset portion 16 projects slightly inward of the base 5, forming a heel 19 resting upon the base 5 when the hook is in closed position. With the heel 19 engaged with the base as described, outward pressure of the pin 2 on the bight portion of the bill 12 will effect more positive locking of the heel 19 with the base 5.

With the pin 2 engaged within the keeper 4, and it is desired to release the pin, the finger nail of the user is inserted in the kerf 18 and pressure exerted outwardly away from the bar 1. Such pressure will swing the keeper hook 11 so as to disengage the protuberance 14 and aline the bill 12 with the studs 8. With the parts in this position, the pin 2 will be free to move outwardly through the slot 6.

I claim:

1. A safety catch comprising a base having stud members extended therefrom, certain of which define a pin-receiving slot and others of which define a hook-receiving slot, a hook swingably mounted in said last-named

slot and arranged to extend across said first named slot, and said hook having a shank provided with a member projecting in an opposite direction to the bill of the hook end serving as a means for swinging the hook and as a means for limiting the swinging movement of said hook in one direction.

5 2. A safety catch comprising a base having an outwardly extending slot to receive a pin, a hook swingably mounted on said base adjacent the outer end of the slot and arranged to close said slot at times, and said hook having an extension projecting in an opposite direction to the bill of the hook end adapted to engage said base to prevent swinging of said hook in one direction.

10 3. A safety catch comprising a keeper having a pin-receiving slot, a hook swingably mounted on said keeper, a friction detent between said hook and keeper to hold said hook in closed position, and said hook having an extension provided with a heel arranged to positively engage said keeper upon swinging movement of said hook in one direction.

15 4. A safety catch comprising a base having a pin-receiving slot, a hook member swingably mounted on said base, said hook member having an extension projecting in a direction opposite to the bill of the hook end provided with a heel adapted to engage said base in one movement thereof, and grip means on said extension outwardly of said heel for manipulating said hook.

20 5. A safety catch comprising a base provided with studs projecting therefrom and defining slots at right angles to one another, a hook pivoted in one slot to the outer ends of two studs, and having its bill normally lying in the slot between two other studs, said hook extending over the other slot, the hook being provided with a straight shank normally lying between the studs and having at its inner end on the side opposite the bill of the hook, an outwardly projecting member for operating the hook, the inner portion of the member engaging the base and limiting the inwardly swinging of the hook.

WILLIAM O. McINTYRE.
